UNITED STATES PATENT OFFICE.

IRWIN J. FRENCH, OF PITTSBURGH, PENNSYLVANIA, ASSIGNOR OF ONE-HALF TO
ALBERT C. GOOD, OF WILKINSBURG, PENNSYLVANIA.

STEAM AND HOT-WATER BOILER.

Application filed December 12, 1922. Serial No. 606,368.

To all whom it may concern:

Be it known that I, IRWIN J. FRENCH, a citizen of the United States, residing at Pittsburgh, in the county of Allegheny and State of Pennsylvania, have invented certain new and useful Improvements in Steam and Hot-Water Boilers, of which the following is a specification.

The invention has for an object to provide, in a boiler of the character mentioned, an improved fluid circulating means including a heating tube arranged for passing directly through the midst of the live coal in the fire box, and which is especially provided for absorbing the combustion in the middle of the fire, which combustion in the conventional form of boilers of the type mentioned, is usually wasted, since only the surface heat has heretofore been utilized and absorbed by the water around the fire box.

Furthermore my invention embodies certain improvements in the grate connections that constitute a part of my complete improved boiler and which are designed for such operation that only the fine ashes from the fire pot or chamber can sift through into the ash pit.

With other objects in view and which will hereinafter appear, this invention consists of a boiler construction which embodies the peculiar arrangement and novel combination of parts set forth in the following detailed description, specifically stated in the appended claims and illustrated in the accompanying drawings, in which:

Figure 1 is a perspective view of a square shaped boiler in which is embodied my improvements.

Figure 2 is a longitudinal section thereof taken substantially on the line 2—2 of Figure 3.

Figure 3 is a transverse section on the line 3—3 on Figure 2.

Figures 4 and 5 are diagrammatic perspective views of circular shaped boilers with my improvements applied.

Figure 6 is a sectional elevation of a further modified type of boiler having my improved arrangement of heating and crown tubes and the said view also illustrates how the boiler can be arranged as a magazine feed boiler.

Figure 7 is a diagrammatic perspective view of an end portion of another form

of boiler hereinafter mentioned, the position of the heating tubes used in connection therewith being indicated in dotted lines.

Figure 8 is a perspective view which illustrates the cylindrical grate sections and the grate bar with which the said grate sections cooperate, the several parts being shown separated.

Figure 9 is a perspective view of one of the end rests for the grate members.

Figures 10 and 11 are diagrams herein-after specifically referred to.

In the drawings, Figures 1 to 3, the boiler is indicated as of square shape and composed of a series of individual sections or units, comprising two hollow end sections 1—1 and a number of intermediate hollow sections 2—2, the latter, with the opposite or end sections 1—1, constituting when coupled up, a boiler body having front, back and opposite ends base flanges 10 for resting on the surrounding rims 30 of a cast base which constitutes the ash pit portion of my improved boiler. The front end of the base portion is provided with an ash pit door 31 that is hinged to a rectangular frame 31^a carried by the base.

The ash pit or base structure of my improved boiler comprises front and back end portions 3 and side portions 33—33, the front portion having an opening to register with the door 31.

The base structure end and side portions may be shaped for being readily assembled without the use of bolts and the like and the corners of the said back and front ends 3 and corresponding corners of the opposite side members 33—33 are each formed with separated and dove-tailed flanges 32—32^a and each adjacent set of said flanges, when the ends and sides of the base are assembled, form separated hollow dove-tailed sockets 35—35 having vertical slots 35^a at their inner base or side, the said slots 35^a in each corresponding set of sockets 35 being in alignment, as is clearly illustrated in Figure 3.

The several dove-tailed sockets 35 in addition to forming means that aid in holding the end and side members of the base structure together, when the several parts are operatively assembled, also function as a means for supporting the peculiarly shaped grate rests or supports 18, one of which is shown

in detail in Figure 9 and will be presently further referred to.

The several sections or units which constitute the boiler body are, as before stated, 5 hollow cast and when assembled to their operative position, as is best illustrated in Figures 2 and 3, all of the several sections are joined and held in communication for the proper circulation therethrough of the 10 water which enters at an inlet 11 in one of the end sections 1 and which, as hot water or steam, passes from the top of the boiler through outlets 21 formed through one or more of the inside sections or units, as is 15 clearly shown in Figure 1 and it should be here stated that communication through the several hollow boiler sections 1 and 2 is established by tubular push nipples 6 (see Figures 2 and 3) which will be hereinafter 20 further explained.

It will be observed that the inlet 11 is in approximate alignment with the lower front water passages between the several sections, 25 from which it will be readily understood that circulation of the heating fluid through the front, back and over the top is greatly aided.

The several inside or intermediate sections 30 of the boiler body are constructed alike, each having a plurality of opposite series of horizontal openings 24, near the upper end, and smaller horizontal openings 25 near the lower front edge, the latter and the upper openings 24, when the parts are assembled, aligning 35 with like openings 24-25 in the adjacent intermediate units to provide clean out and clinker openings, as will be presently further explained.

The openings 24 serve to provide for the 40 ready placement of the clean out doors 5. The clinker openings 25, before mentioned, are so positioned with respect to the grate surface of the boiler as to provide for the ready breaking up of the clinkers that lodge 45 on the grate members 37 hereinafter described in detail.

Like the openings 24 the clinker openings 25 are normally closed by doors 50.

The adjacent two centrally disposed intermediate boiler sections have transverse openings 27 at the front end which extend across the full width of such end and when the several units are assembled the several 50 openings 27 constitute the fuel feed openings, as is clearly shown in Figures 1 and 2.

The said fuel openings are adapted to receive the sleeve 70 cast on the inner face of a door holding rectangular frame 71, which carries hinged thereto a door 7.

60 At their front, back and top surfaces each of the several units, which, when assembled, constitute the boiler body, may have dovetailed assembling lugs 28-28, so located upon the faces of their respective units and 65 relatively to the push nipples 6, before men-

tioned, that when the said nipples are assembled the like lug portions 28-28 on adjacent edges of pairs of the boiler sections align and are disposed for conveniently fitting thereon, steel clamp devices 8, adapted when the clamp device is hammered home to firmly clamp and draw together the lugs 28-28 on the adjacent or abutting edges of the pairs of boiler sections and thereby securely hold the several sections or units in their desired assembled adjustment.

By thus constructing the several boiler sections or units, a simple and effective assembling means is provided whereby the parts are tightly and practically assembled 80 in such a manner that the strain of assembling is exerted upon the individual unit and not accumulatively as in the case of a bolt drawn assembly.

To prevent the clamps 8 from becoming accidentally displaced, the said clamps when fitted in operative position, may be secured by clamp screws 81 that thread through the clamps 8 and engage the boiler body, as 90 shown.

To provide for the free circulation of the heating fluid through the several boiler sections and at the same time effect a practically fluid-tight closure between the several sections or units when they are assembled, as is 95 best shown in Figures 1, 2 and 3, each of the units or sections has apertures 10°-20° and these at the outer sides are finished to provide smooth contacting surfaces.

As is best shown in Figure 2, the several 100 fluid passages 10°-20° are located midway the sets of clamping lugs 28-28 adjacent thereto, the reason for which will presently appear.

The fluid openings or passages 10°-20° 105 are so located that when the sections or units are assembled, the passages in the abutting walls of adjacent sections or units register in such manner that they will close and fit tightly over the tubular push nipples 6 and since the said push nipples 6 are located midway their adjacent sets of operative lugs 28, it follows that by so locating the boltless elements for clamping the sections or units together a positive fluid-tight joining 110 of the several parts is provided for, since the maximum drawing up strains of the adjacent sections or units is located at the places where most needed for effecting the desired fluid-tight connection of the several sections 120 or units, as before stated.

Each boiler unit or section is formed with hollow passages or crown baffles 29 and those of the central units 2 are joined centrally thereof with a hollow drop crown 29a, all of 125 which are in circulating communication with the heating fluid and positioned in such a manner as to present a maximum area of heat absorbing surface to the passing products of combustion, (see Figures 2 and 3). 130

Each said central unit is provided, at such places as is found desirable, in practice, with openings 23^a which aid in cleaning said sections of the said core after casting. The 5 openings 23^a are closed by screw plugs 23^b.

As is well known to those familiar with the manufacture and use of boilers of the type mentioned, the heat in the boiler fire box is generally consumed by internal combustion and only the surface heat is absorbed by the water surrounding the fire box. 10

In my construction of boiler each intermediate boiler section or unit is formed with a 15 heating tube 36 which extends across from the lower front to the lower back edge of the section, as best shown in Figures 2 and 3. The heating tubes 36 are preferably oval or elongated shape in vertical direction and are 20 cast integral with or have their opposite ends in communication with the water spaces in the front and back walls of the boiler section of which they form a part.

By providing a cross tube 36 along the 25 lower end of each intermediate boiler section or unit, as stated, the said tubes pass through the midst of the live coal in the fire box when the boiler is working.

By referring more particularly to Figures 30 2 and 3 of the drawings, it will be noticed the several tubes 36 divide the lower part of the fire box into a series of separate chambers or pockets 17 each of which communicates at the front end with a clinker opening 35 25 and since the lower end of each cross tube 36 is disposed between the adjacent faces of a pair of cylindrical grates 37, (presently further explained) any one of the separated fire box pockets 17 can be conveniently 40 cleaned out as may be necessary, without disturbing the remaining portions of the fire box.

By providing the cross heating tubes 36 and arranging them in the manner shown 45 and described, the efficiency of the boiler is materially increased by reason of the said heating tubes absorbing the combustion in the middle of the fire box, a combustion heretofore wasted, as before mentioned.

50 It is understood when it is desired to remove one or more of the boiler units or sections for cleaning or repairing, it is only necessary to drive off the clamping devices 8 that join the section or sections to be removed, thus making it possible to conveniently remove and restore a unit or section without materially disturbing the connected arrangement of the remaining boiler sections.

60 In my construction of boiler and in the preferred form thereof, as shown in Figures 1 to 3, the grate is composed of a plurality (five being shown) of rotatably mounted members each of which is in the nature of a basket grate composed of three sections

37, each provided with a non-circular axial bore 37^a to adapt them to slidably fit onto a cast steel bar 38 which is formed with rounded ends or journals 38^a—38^a for fitting socket bearings 18^a in the grate rests or supporting members 18 hereinbefore mentioned and one of which is detailed in Figure 9. 70

The journal portions 38^a of the bars 38 at the outer end thereof, are sufficiently long to extend through apertures 40 in the front 75 end of the boiler base and then terminate in non-circular heads 41 for receiving a shaker or crank handle in the usual way.

As is best shown in Figure 3, the cylinders 37 of two adjacent grate members have 80 such close relation and are so designed that the said grates will afford the desired agitation of the fuel when rocking the said grates and at the same time permit only the fine dust to go through the grates, the clinkers 85 being kept at the top surface of the grate and by reason of the separated fire pot pockets 17 formed between the adjacent pairs of tubes 36 the said clinkers are held for being readily pulled out through the 90 clinker openings 25 through the front wall of the boiler when the clinker doors therefor are removed.

To provide against clogging of clinkers between the adjacent faces of the outermost 95 ones of the grates 37 and their adjacent internal walls of the opposite end sections 10—10, the latter have grate-like flanges 37^b along their inner edges, as is indicated in Figure 3. 100

A boiler as constructed and described provides for a compact assemblage of the different parts or sections and in such manner that the operation of setting up the boiler can be effected in a minimum amount 105 of time and labor, since the time and labor usually required for connecting boiler sections or parts by bolts or rivet devices is saved as all that is necessary for assembling the several sections of my improved construction of boiler, into operative condition, and to secure the parts in rigid relation, is the driving on of the clamping devices 8 that engage the dove-tail lugs 28 on the boiler sections, as before described, and 110 as clearly illustrated in the drawings.

As before mentioned, the grate members are mounted in grate supports 18 located within the front and back end confines of the boiler base 3. In my arrangement, the 115 said supports 18 also function to aid in holding the front and back ends and the opposite sides of the base structure firmly together.

Each of the grate supports 18 includes opposite pendent ends 19 that turn inwardly at an angle of substantially 45° and at their 120 top and bottom ends the said inturned members 19 are formed with a dove-tailed vertically slotted hollow lug 16 130

and the said ends or webs 19 that carry the upper and lower lugs 16-16, are adapted for sliding into position through the vertical slotways 35^a formed between the 5 dove-tail guides 35 in the corners of the base structure, as is best shown in Figures 2 and 3.

Figures 4 and 5 of the drawings diagrammatically illustrate circular types of 10 boilers with my improvements embodied thereon, and when applied to such types of boilers a pair of heat tubes are preferably extended across the fire chamber, the latter, as shown, being substantially square shape 15 in the horizontal plane. In the form shown in Figures 4 and 5 a plurality of crown tubes 36^a are also provided.

When arranged as shown in Figures 4 and 5, the body portion of the boiler is 20 formed to seat on a base cast with an internal flange 39 that constitutes the rest for the boiler body.

When but two heating tubes are used, as 25 shown in Figure 4, a grate section 37 is located between the abutments of the two tubes 36, and other grate sections 37 are located between the tubes 36 and their adjacent walls of the fire box, the lower internal edges of which terminate in grate-like flanges, as indicated.

When the grates are arranged as shown 30 in Figure 4, the outer journals thereof that project through the front wall of the boiler each carry a chain wheel 77, the several 35 wheels being adapted for engagement with the endless sprocket chain 78, as is best shown in Figure 5, which figure also shows a journal in the center grate bar extended 40 for being engaged by a shaker or crank handle.

In the form shown in Figures 4 and 5 the 45 said body may have wedge shaped locking flanges or lugs 79 adapted for cooperating with a top or crown section (not shown) which, in practice, is also provided with like 50 lugs for being coupled with the lugs 79 by clamp devices, such as is shown in my preferred construction hereinbefore mentioned.

When the number of grate bars shown in 55 Figures 4 and 5 are used, the clinker doors are preferably arranged as shown in Figure 5.

Figure 6 diagrammatically illustrates another type or form of boiler with my 60 improvements embodied therein. In this particular form, the boiler front or side is formed with a fuel opening 85 which is adapted for receiving the sleeve or cuff of a magazine or filler device 86 whose flange or throat portion is so shaped that it can be 65 snugly entered into the said flue opening.

While my improvements are particularly 65 designed for the building up of new boilers along the line stated the heating tube feature may be readily adapted for or applied to high pressure boilers already installed. For boilers already installed, the heating tubes 36 may have their ends suitably shaped 70 for being either welded or riveted in the boiler casing, as is indicated in Figures 10 and 11.

In this application I lay no claim to the 75 base and grate structure per se since that forms the subject matter of an application filed Jan. 11, 1924, Serial No. 685,709, patented May 27, 1924, Patent No. 1,495,475.

From the foregoing taken in connection 80 with the accompanying drawings the complete construction, the manner of manufacturing and setting up my improved boiler 85 and its advantages will be readily apparent to those familiar with the manufacture and installation of boilers of the type hereinbefore mentioned.

What I claim is:

1. A boiler composed of end and intermediate sections fitted together side by side and enclosing a fire box, surrounded top, sides and ends by a water space, a base and grate structure over which said sections set, said base and grate structure including cylindrical-cage grate elements extending from front to back with their axes substantially aligning with the joints between said sections, said cages projecting up above the bottom plane of said sections, vertically elongated water tubes extending from the front to the back of said intermediate sections through the fire box and communicating with said water spaces, said tubes projecting between said adjacent pairs of cylindrical-cage grate elements and extending below the level of the top of said grate elements into proximity with the same. 95

2. A boiler of the boltless type including 100 a body enclosing a fire box surrounded front, back, sides and top by a water jacket, a base structure onto which said body is set, grate elements mounted on said base structure and including rotatable cylindrical-cages which project up above the bottom of 105 said body into the fire box thereof, said body having vertically elongated elliptical water tubes extending parallel to the grate elements from front to back of the fire box and in planes intermediate the axes of adjacent 110 pairs of grate elements and connected with said water jacket, said tubes extending down between said adjacent grate cages and into proximity thereto. 115

IRWIN J. FRENCH.
